(57) **CLAIM**

The ornamental design for a belt hanger, as shown and described.

DESCRIPTION

1.1 is a top, front, right side perspective view of a belt hanger showing a first embodiment of the new design;

1.2 is a front view thereof;

1.3 is a rear view thereof;

1.4 is a top view thereof;

1.5 is a bottom view thereof;

1.6 is a left side view thereof; and

1.7 is a right side view thereof.

2.1 is a top, front, right side perspective view of a belt hanger showing a second embodiment of the new design;

2.2 is a front view thereof;

2.3 is a rear view thereof;

2.4 is a top view thereof;

2.5 is a bottom view thereof;

2.6 is a left side view thereof; and

2.7 is a right side view thereof.

5.1 is a top, front, right side perspective view of a belt hanger showing a third embodiment of the new design;

5.2 is a front view thereof;

5.3 is a rear view thereof;

5.4 is a top view thereof;

5.5 is a bottom view thereof;

5.6 is a left side view thereof; and

5.7 is a right side view thereof.

6.1 is a top, front, right side perspective view of a belt hanger showing a fourth embodiment of the new design;

6.2 is a front view thereof;

6.3 is a rear view thereof;

6.4 is a top view thereof;

6.5 is a bottom view thereof;

6.6 is a left side view thereof; and

6.7 is a right side view thereof.

8.1 is a top, front, right side perspective view of a belt hanger showing a fifth embodiment of the new design;

8.2 is a front view thereof;

(Continued)

- 8.3 is a rear view thereof;
- 8.4 is a top view thereof;
- 8.5 is a bottom view thereof;
- 8.6 is a left side view thereof; and
- 8.7 is a right side view thereof.
